(57) **CLAIM**

The ornamental design for a lock for closable box, as shown and described.

DESCRIPTION

FIG. 1 is a perspective view of an exemplary embodiment of a lock for closable box;

FIG. 2 is a front view of the lock for closable box shown in FIG. 1;

FIG. 3 is a back view of the lock for closable box shown in FIG. 1;

FIG. 4 is a left side view of the lock for closable box shown in FIG. 1;

FIG. 5 is a right view of the lock for closable box shown in FIG. 1;

FIG. 6 is a top view of the lock for closable box shown in FIG. 1; and,

FIG. 7 is a bottom view of the lock for closable box shown in FIG. 1.

The phantom lines are provided for illustrative purposes only, and form no part of the claimed design.

1 Claim, 4 Drawing Sheets See application file for complete search history.
